UNITED STATES PATENT OFFICE.

ARON FRIEDMAN, OF CHICAGO, ILLINOIS.

COMBINED MATCH-SAFE AND CIGAR-CUTTER.

SPECIFICATION forming part of Letters Patent No. 771,977, dated October 11, 1904.

Application filed July 16, 1904. Serial No. 216,805. (No model.)

To all whom it may concern:

Be it known that I, ARON FRIEDMAN, a citizen of the United States, and a resident of Chicago, in the county of Cook and State of Illinois, have invented certain new and useful Improvements in a Combined Match-Safe and Cigar-Cutter, of which the following, when taken in connection with the drawings accompanying and forming a part hereof, is a full and complete description, sufficient to enable those skilled in the art to understand, make, and use the same.

This invention relates to a match-safe designed to be carried in the pocket; and the object of the invention is to obtain a combined match-safe and cigar-cutter which will be slight in appearance, not bulky, economical in construction, and durable.

In the drawings referred to, Figure 1 is a side elevation of a combined match-safe and cigar-cutter embodying this invention with the doors or covers thereof closed. Fig. 2 is a side elevation of a combined match-safe and cigar-cutter embodying this invention with the doors or covers thereof open. Fig. 3 is a front or edge elevation of the combined match-safe and cigar-cutter illustrated in Figs. 1 and 2. Fig. 4 is a plan view of the blank from which the knife of the cutter of the device is formed up. Fig. 5 is a plan view of the blank from which the door or cover of the match-safe end of the device is formed up. Fig. 6 is a plan view of the blank from which the spring forming the front edge of the device is formed up. Fig. 7 is a perspective of the spring of the device. Fig. 8 is a plan view of the blank from which the sides and back of the match-safe are formed up.

A reference-letter applied to designate a given part is used to indicate such part throughout the several figures of the drawings wherever the same appears.

45 A is the blank from which the sides and back of the device are formed up.

a a are broken lines on which blank A is bent, a' a' being the sides, and a² the back, of the combined match-safe and cigar-cutter.

50 B Bare beads in sides a' a'. The beads B B

in the end of sides a' a' adjacent to the cutter of the device are used to hold the partition D, forming the bottom of the match-safe, and the beads B B at the other end of the sides a' a' are there placed to give a symmetrical appearance to the device. 55

C C' are holes in sides a' a', in which the end of a cigar designed to be cut is inserted.

D D' are holes in blank A, in which the ends e e of spring E are inserted and riveted when 60 the several parts of the device are assembled. Spring E is made of sheet metal, as steel or hard brass, and the ends e e of the wings e' e' are bent up on lines indicated by broken lines e² e². 65

F is a blank bent up on lines f f' to form the cutter of the device, and f' f' are holes in blank F, through which a pin or rivet G extends to hold the cutter in place when the several parts of the device are assembled. 70

The cutter of the device turns on pin G when operated, and g is the cutting edge thereof, which moves adjacent to one of the sides a' over hole C to cut the end of a cigar off when so operated. 75

H is the blank from which the cover or door of the match-safe of the device is formed up, and h h are the lines on which such blank is formed up to obtain the flies or wings h' h', in which are placed holes h² h² to receive pin G, 80 on which such cover turns.

When the parts are assembled, the blank F, formed up to obtain the cutter g, and the cover obtained from blank H are yieldingly held in a closed position by the spring F when 85 closed and in an open position when opened. The bottom D is slid into place in beads B B before the pins or wires G G and ends e e of spring E are inserted in the respective holes therefor and riveted. 90

Having thus described my invention, what I claim is new, and desire to secure by Letters Patent, is—

1. In a combined match-safe and cigar-cutter the combination of a shell consisting of 95 sides and a back formed up of sheet metal, such sides provided with heads and one of such sides provided with a hole adapted to receive the end of a cigar, a bottom to the match-safe, consisting of a plate slid into the beads in 100

the sides, a cover formed up from sheet metal and pivotally attached to the sides, a cutter formed up from sheet metal, and pivotally attached to the sides, and a spring front consisting of sheet metal formed up and attached midway of its ends to the sides; substantially as described.

2. In a combined match-safe and cigar-cutter the combination of a shell consisting of sides and a back formed up of sheet metal, a partition secured in place between the ends of the sides, a spring front, such spring consisting of sheet metal secured between its ends

to the sides, a cover pivotally attached to the sides near one end of the sides and a cutter pivotally attached to such sides near the other end thereof, such cover, cutter and spring related so that the cover and the cutter are respectively held in a determined open position and in a determined closed position by the spring; substantially as described.

ARON FRIEDMAN.

In presence of—

CHARLES TURNER BROWN,
CORA A. ADAMS.
